UNITED STATES PATENT OFFICE.

HEINRICH F. D. SCHWAHN, OF KANSAS CITY, MISSOURI.

PROCESS OF MAKING SOAP.

SPECIFICATION forming part of Letters Patent No. 396,348, dated January 15, 1889.

Application filed March 9, 1888. Serial No. 266,734. (Specimens.)

To all whom it may concern:

Be it known that I, HEINRICH F. D. SCHWAHN, of Kansas City, in the county of Jackson and State of Missouri, have invented 5 a certain new and useful Improved Process of Saponifying Fatty Substances, of which the following is a full, clear, and exact description.

The invention consists in a process, hereinafter described, by which a pure soap may be made very quickly and without attaining a boiling-temperature in the manufacture.

I will first describe the process where pure fat—such as tallow—is used:

One hundred pounds of tallow are melted at 15 a temperature of about 120° Fahrenheit. To this, after melting, are added fifty pounds of lye—generally known as pure lye or caustic soda—having a strength of 45° Baumé. The 20 mass is then mixed until it becomes plastic, the temperature being maintained at about 120° Fahrenheit. Then to the mass is added one hundred and twenty pounds of a soap solution made by dissolving twenty pounds of 25 hard soap in one hundred pounds of water at a temperature of 150° Fahrenheit. The

ingredients are then thoroughly mixed and the temperature raised to about 180°. A chemical union is now perfected between the fat, the alkali, and the water. There will be a 30 residue of the lye, which will sink to the bottom and carry with it any impurities which may be in the mass, such impurities being ejected with the lye as the chemical union takes place. The soap becomes hard on cooling. 35

In place of the soap solution described an equivalent quantity of soft soap may be used.

I claim as my invention—

The described method of making soap, consisting of melting the fat, mixing therewith the lye while at a temperature of about 120° Fahrenheit, mixing with this the described soap solution while at a temperature of about 150° Fahrenheit, and then raising the temperature to about 180°, substantially as set forth. 40 45
